UNITED STATES PATENT OFFICE.

GEORGE A. JOHNSON, OF CHICAGO, ILLINOIS, ASSIGNOR TO WILLIAM H. MINER, OF CHAZY, NEW YORK.

DRAFT-RIGGING.

1,273,865.

Specification of Letters Patent. Patented July 30, 1918.

Application filed September 20, 1916. Serial No. 121,125.

To all whom it may concern:

Be it known that I, GEORGE A. JOHNSON, a citizen of the United States, residing at Chicago, in the county of Cook and State 5 of Illinois, have invented a certain new and useful Improvement in Draft-Riggings, of which the following is a full, clear, concise, and exact description, reference being had to the accompanying drawings, forming a 10 part of this specification.

This invention relates to improvements in draft riggings.

The object of this invention is to provide a draft rigging having an articulated yoke 15 combined with an improved design of stop casting so arranged as to permit the draw bar and yoke to swing about an axis substantially opposite the centers of the stop castings.

20 In the drawing forming a part of this specification, Figure 1 is a horizontal section of a portion of a car, taken just above the gear and illustrating my improvement in connection therewith. Fig. 2 is a side 25 elevation of the improved yoke employed with my invention. And Fig. 3 is a vertical sectional view of the yoke taken substantially on the line 3—3 thereof.

In said drawing, 10—10 denote channel 30 shaped center sills to the inner faces of which are applied my improved stop castings A—A. Each of the latter is designed for a tandem gear and is provided with main stops 11, 12, 13 and 14 for coöperation 35 with the front main follower 15, front intermediate follower 16, rear intermediate follower 17, and rear main follower 18, respectively. Intermediate the sets of followers are interposed the springs 19 and 20 40 in the usual manner. Each of said stop castings A is also provided with a series of limiting stops 21 for limiting the compression of the springs in the usual manner. The draw bar 22 is operatively connected 45

with the tandem gear by the improved yoke designated generally by the reference B. Said yoke B, as shown, comprises two sections or parts B¹ and B². The section B¹ is of substantially U shape and has upper 50 and lower arms 24 and 25 connected by the vertical portion 26, said arms 24 and 25 being attached to the draw bar in any suitable manner, as for instance, by the rivets 27. The rear part B² of the yoke is of sub- 55 stantially rectangular form having upper

arm 28, lower arm 29, rear vertical wall 30 and front vertical wall 31, thus forming a rectangular pocket to receive the rear element of the tandem gear. The two parts B¹ and B² are pivotally or articulately connected by means of a series of spaced, overlapping, perforated ears or lugs 32 and 33 formed respectively on the rear of the member B¹ and front of the member B², a heavy pivot pin or bolt 34 extending through said 60 ears 32 and 33. The bolt is held in position by any suitable means such as the cotter 35. It will be noted from an inspection of Fig. 3 that the pivot pin 34 is placed in quadruple shear, thus providing great strength in the 70 connection.

In order to insure the draw bar swinging about an axis substantially at the centers of the castings, each of the castings A is provided with an upper follower guiding and 75 strengthening flange 36. Each of said flanges 36 between the middle post and rear stop has its edge 37 extended parallel to the center line of the gear, thus maintaining the rear part B² of the yoke always substantially 80 parallel to the axis of the gear in both buffing and pulling movements. Forwardly of the center posts of the castings, the flanges 36 are cut away or tapered or inclined outwardly as indicated at 38, it being understood 85 that the center posts of the castings are deeper than the front stops. By this arrangement, it is obvious that the draw bar and yoke may swing radially as indicated by the dotted lines in Fig. 1, about 90 the center posts of the stop casting as fulcrums, while a direct straight line pull or buff is always maintained on the followers of the rear element of the tandem gear, thus minimizing the tendency of the parts to 95 bind. The yoke and elements of the gear are supported by any suitable means such as the saddle plates 39 which are detachably bolted to the lower flanges of the sills.

I claim:

1. In a draft rigging, the combination 100 with tandem stop castings, said castings being deeper at the centers than at the forward ends thereof, of a yoke articulated at a point normally substantially opposite the centers of said castings, and means on said castings at the rear of the centers thereof adapted to confine the rear portion of the articulated yoke to substantially straight 105 line movements parallel to the axis of the 110

gear, the front portion of the articulated yoke being adapted to have radial movement.

2. As an article of manufacture, a stop casting for draft riggings, said casting being provided with front, rear, and intermediate main stops for coöperation with followers of a tandem gear, said casting having an upper flange tapered from the center 10 stop to the front main stop and of substantially uniform width from the center stop to the rear stop.

3. In a draft rigging, the combination with tandem stop castings, each having an 15 upper guide flange tapered from the middle thereof toward the front end of the casting and of substantially uniform width from the center of the casting to the rear thereof, of an articulated yoke, the rear portion of said 20 yoke being confined to substantially straight line movements parallel to the axis of the gear by the rear portions of said flanges, the

front portion of the yoke being permitted a radial movement.

4. In a draft rigging, the combination 25 with draft sills and stop castings secured to the inner faces thereof, each of said stop castings having an upper flange tapered from the center thereof toward the front end of the casting, said flanges from the 30 center of the casting extending substantially parallel to the center line of the draft rigging, of a two-part yoke, said parts being pivotally connected opposite the centers of said castings, whereby the front portion 35 of the yoke may swing radially about the center of the castings as fulcrums.

In witness that I claim the foregoing I have hereunto subscribed my name this 18th day of Sept., 1916.

GEORGE A. JOHNSON.
